(57) **CLAIM**

The ornamental design for a dress with a control layer, as shown and described.

DESCRIPTION

FIG. 1 is a front elevational view of a dress with a control layer;

FIG. 2 is a rear elevational view thereof;

FIG. 3 is a left side elevational view thereof;

FIG. 4 is a right side elevational view thereof;

FIG. 5 is a top elevational view thereof;

FIG. 6 is a bottom elevational view thereof;

FIG. 7 is a front elevational view of a dress with a control layer, wherein the dress has been turned inside-out;

FIG. 8 is a rear elevational view thereof;

FIG. 9 is a left side elevational view thereof;

FIG. 10 is a right side elevational view thereof;

FIG. 11 is a top elevational view thereof; and,

FIG. 12 is a bottom elevational view thereof.

The outline of a dress shown in broken lines illustrates environmental subject matter and forms no part of the claim.

1 Claim, 10 Drawing Sheets
